Primary Examiner — Kimberly Barnes*Assistant Examiner* — Alexandria Dubus(74) Attorney, Agent, or Firm — John Rizvi; John Rizvi, P.A.—The Patent Professor ®(57) CLAIM

The ornamental design for a purse with wave features as shown and described.

DESCRIPTION

FIG. 1 is a front isometric view of a purse with wave features showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front isometric view of the purse with wave features with a flap in an open position.

The broken lines illustrate a stitching and form part of the claimed design.
